FIG. 3.

UNITED STATES PATENT OFFICE.

ISIDOR TORNBERG, OF NEW YORK, N. Y., ASSIGNOR TO R. HOE AND CO., OF NEW YORK, N. Y., A CORPORATION OF NEW YORK.

INTAGLIO-PRINTING MACHINE.

1,286,450.

Specification of Letters Patent.

Patented Dec. 3, 1918.

Application filed February 19, 1917. Serial No. 149,437.

To all whom it may concern:

Be it known that I, ISIDOR TORNBERG, a citizen of the United States, residing at New York city, county of Kings, and State of New York, have invented certain new and useful Improvements in Intaglio-Printing Machines, fully described and represented in the following specification and the accompanying drawings, forming a part of the same.

This invention relates to certain improvements in intaglio printing machines.

For certain classes of work, intaglio machines are constructed with copper or other engraved cylinders, which run in or are continuously supplied with ink. Where the machine is a rotary machine, arranged to print on a web, these engraved cylinders have coöperating therewith impression cylinders or rolls of rubber or other suitable material, the web being printed between the engraved plates and these rubber impression cylinders or rolls.

In this type of machine it frequently happens that it is necessary, for various reasons, to stop the printing operation after the same has been started and the engraved cylinder inked up. It is necessary, however, that the engraved cylinder continuously rotate in the ink, or be continuously supplied with ink, so that the ink will not dry on the engraved surface of the cylinder.

To effect a stopping of the printing operation it has been proposed to provide adjusting means whereby the rubber impression cylinders or rolls may be moved out of printing relation with the engraved printing cylinders. Where, however, a plurality of printing units, each including an engraved cylinder and its coöperating rubber impression roll, are employed, as in perfecting machines, it is desirable that both the rubber impression rolls or cylinders may be moved out of printing relation with the printing cylinders simultaneously. This need for operating the rolls simultaneously may occur suddenly, and it is necessary that the means provided be such that stoppage of the printing relation may take place with the least possible loss of time.

It is further desirable, however, that the mechanism employed for moving the impression rolls out of printing relation be such that any of the rolls may be moved independently of the others, and it is further de-

sirable that this mechanism should be of such character that it will be unnecessary to slip gears or disconnect clutches, the wrong positions of which might be overlooked and cause the mechanism to be in such position that quick stoppage of the run of the web could not be effected.

It is an object of the present invention to provide in an intaglio printing machine employing a plurality of printing couples a simple and convenient mechanism whereby the printing relation between the impression cylinders of rubber or other suitable material and the engraved printing cylinders, may be simultaneously and quickly broken, thereby stopping the printing operation without interrupting the running of the engraved printing cylinders.

It is a further object of the invention to provide such a construction in which the impression rolls may have such printing relation broken independently of each other through a mechanism which obviates the necessity of employing slipping gears or clutches which have to be manipulated so that danger of the parts being in wrong position for quick and proper operation of the mechanism is eliminated.

With these and other objects in view, the invention consists in certain novel parts and combinations which will be specifically described in conjunction with the accompanying drawings, in which—

Figure 1 is a side elevation of so much of an intaglio printing machine as is necessary for an understanding of the invention, the machine shown employing two printing couples, certain parts being broken away;

Fig. 2 is a horizontal view, partly in section, on an enlarged scale, the view being taken on line 2—2 of Fig. 1;

Fig. 3 is an enlarged view, partly in section, of the adjusting mechanism for simultaneously adjusting both impression rolls;

Fig. 4 is a view, partly in section, of part of the construction shown in Fig. 3, the section being taken on line 4—4 of Fig. 3;

Fig. 5 is detail sectional view, taken on line 5—5 of Fig. 3; and

Fig. 6 is a fragmentary view of certain clutch and ratchet mechanism employed.

Referring now to the drawings, the machine chosen to illustrate a concrete embodiment of the invention is a rotary machine having a plurality of printing couples, the

number in the present instance being two. The members of these couples are, as shown, cylinders, the form cylinders having engraved surfaces of copper or other suitable material and being marked 1, 2. Coöperating with these engraved cylinders are the impression cylinders or rolls 3, 4, which, in the present instance, are rubber rolls. As is usual in intaglio printing machines, these rubber impression rolls or cylinders are mounted so as to have a yielding contact with the engraved cylinders, and in the present construction the cylinders are arranged vertically, the impression cylinder being above. A convenient means for mounting the impression cylinder is that illustrated in which the rolls are carried in hubs 5, these hubs having projections 6 entering sockets 7 in blocks 8 sliding in suitable ways 9 in the frame 10 of the machine, for a purpose hereinafter referred to. In the sockets 7 are springs 11 which take against the projections 6 of the hubs and the tops of the sockets, the tension of these springs being adjustable by means of rod 12 and adjusting nuts 13, this construction permitting easy adjustment of the tension of the springs, it being understood that this construction is duplicated on the other side of the machine. The engraved cylinders 1, 2, after inking up, are continuously rotated during the operation of the machine, and are continuously fed with ink in any suitable manner, as by rotating in a fountain (not illustrated). It frequently happens that it is necessary to break the printing relation between the printing members of one of the couples without stopping the rotation of the printing cylinder or without stopping the printing operation of the other couple. In machines embodying the invention, therefore, means are provided whereby this is effected, and while these means may be carried out in various ways, in the present instance mechanism is employed by which the impression cylinders or rolls may be given a vertical movement independent of each other to bring them out of and into contact with their coöperating printing cylinders. While the particular means employed for this purpose may be of any desired character, in the particular construction illustrated the blocks 8 before referred to, in which the impression cylinders or rolls are mounted, are given a sliding movement in the ways 9 by means of screws 14, these screws being mounted in recesses in the frame. These screws are threaded through ears 15 having threaded extension 16 screwed into the blocks 8. By rotating these screws the blocks are raised or lowered, as desired. The operating screws 14 take bearing in the recesses in the frame between the ways 9 and are rotated by means of spiral gears 17 on their upper ends, these spiral gears coöperating with spiral gears

18 on shafts 19, 20 extending across the machine, one such shaft being provided for each of the couples, these shafts being rotated by suitable hand operated means, as hand wheels 21, 22 located at one side of the machine. With this construction, the impression cylinders or rolls 3, 4 may be adjusted as desired, and the printing relation between them and the coöperating printing cylinders interrupted or stopped as desired without stopping the operation of the printing cylinders.

It frequently happens, however, in these machines, and particularly in perfecting machines employing two printing couples, that it is desirable to stop the printing operation of both couples simultaneously, and as the necessity for this occurs suddenly it is desirable that means be provided so that this can be accomplished in the shortest possible time. Machines constructed in accordance with the invention, therefore, will be provided with mechanism whereby this may be accomplished, and in the preferred construction this mechanism will be such that the individual or independent raising or lowering of the impression rolls or cylinders can be effected without slipping gears or disconnecting clutches which, if inadvertently left in the wrong position, would interfere with the quick and proper operation of the mechanism. While this may be accomplished in various ways, in the particular construction illustrated there are provided on one side of the machine a pair of independent axially aligned shafts 23, 24, these shafts being supported in brackets 25 depending from a suitable cross frame 26. At their outer ends these shafts are provided with spiral gears 27, 28, which mesh with similar gears 29, 30 on the shafts 20, 19, before referred to. It will be seen that by rotating these shafts in unison the shafts 20, 19 will be likewise rotated and the impression cylinders or rolls raised or lowered as the case may be.

Various means may be employed for rotating these shafts together, but the means will include connections which will also permit them to be independently rotated so that the impression cylinders or rolls may be independently raised or lowered without the necessity of having to manually slip gears or operate clutches. In the particular construction illustrated, the shaft 24 has keyed or feathered on its inner end, so as to turn therewith, a clutch 31, and the shaft 23 has on its extreme inner end a clutch 32, this clutch entering a recess 33 in the clutch face 31. The clutches 31, 32 are formed with a series of ratchet teeth 34, 35, respectively, which are cut in their inner faces, so as to coincide with each other around the clutch faces, as illustrated in Fig. 4. The shaft 23 is also provided with a clutch 36 loosely mounted thereon, this clutch being pro-

vided on its inner face with a recess 37 in which seats a second clutch 38, fastened or otherwise secured on the shaft so as to turn therewith; the clutch faces 36, 38 having cut 5 on their faces ratchet teeth 39, 40, respectively, which coincide circumferentially of the clutch faces.

Coöoperating with these clutches is an actuator and means for operating the actuator, 10 so as to cause it to operate the clutches for rotating the shafts simultaneously, in the direction desired. While the particular construction of this actuator may be somewhat varied, in the particular construction 15 illustrated it is in the form of a block 41 mounted so as to rotate freely on the shaft 23 before referred to, and have an easy sliding movement along the shaft. In order that the actuator may have this easy longitudinal and rotary motion along and about the shaft 23, it is preferably mounted thereon through ball bearings 42, the balls being held in position by suitable retaining rings 43 on each end of the actuator block. This 20 actuator block is provided on each face with ratchet teeth 44, 45, the ratchet teeth 45 being adapted to engage with the teeth 34, 35 on the clutch faces 31, 32, and the teeth 44 being adapted to engage with the teeth 39, 30 40 on the clutches 36, 38. The actuator block is operated in any suitable manner to cause it to have a longitudinal movement in either direction on the shaft 23 to cause it to engage the clutches on either side of it. 35 In the particular construction illustrated, the actuator block is formed with a spiral gear 46 having its teeth cut at an angle of about 45°, which meshes with a spiral gear 47 feathered by a key 48 to the hub 49 of a 40 hand wheel 50 supported on a stud 51 held in suitable bracket 52 depending from the cross frame 26 before referred to.

With the construction so far described, it will be seen that by rotating the hand wheel 45 50 to the right, as shown in the figures, a longitudinal motion will, because of the pitch of the gears, impart a longitudinal motion to the right to the actuator block, this motion, through the ball bearing construction referred to, being very easily imparted 55 to the block. When the hand wheel is thus operated, the clutch teeth 45 on the actuator block engage with the teeth 35 of the clutch 32 which, as before stated, is fast on the shaft 23, and the teeth 34 of the clutch 31 also fast on the shaft 24. Through these connections the actuator causes the shafts 23, 24 to rotate in unison and will effect, in the particular construction illustrated, a 60 simultaneous raising of the impression rolls or cylinders through the connections above described. By the rotation of the hand wheel 50 in the opposite direction, the actuator block is moved to the left to cause 65 the rotation of the shafts 23, 24 in the oppo-

site direction. The connections by which the actuator block thus causes the opposite rotation of the shafts is, in the particular construction illustrated, effected through a short shaft 53 supported above and parallel 70 with the shafts 23, 24 in suitable hubs 54 carried on two of the brackets 25 before referred to. This shaft has fast thereon gears 55, 56 which mesh with gear teeth 57, 58 formed, respectively, on the peripheries of 75 the clutches 36, 31, before referred to. Through these connections, when the hand wheel 50 is rotated to the left, as shown in the figures, the ratchet teeth 44 of the actuator block engage with the ratchet teeth 39, 80 40 on the clutch members 36, 38, and, through them, gear 55, shaft 53, gear 56, and clutch 31, operate simultaneously to rotate both shafts 23, 24 in the opposite direction, thereby effecting the simultaneous lowering 85 of the impression cylinders or rolls.

As has been described, the actuator block is very easily movable along the shaft 23, because of the ball bearing construction. If it is desired to independently adjust or stop 90 the printing relation between either one of the couples independently of the other, the rotation through shafts 19, 20 of either of the shafts 23, 24, would cause the actuator block to become disengaged with whichever 95 of the clutches it might be in engagement with. The construction described, therefore, avoids the use of gears or clutches which have to be manually manipulated or operated to get them in the correct position, 100 and any difficulties due to their being in the wrong position when an adjustment is to be made, are eliminated.

While the invention has been shown and described in its preferred form, it will be 105 understood that certain changes and variations may be made in the particular construction and arrangement of the parts without departing from the invention, and it is furthermore understood that as to some of 110 its features the invention is applicable to intaglio printing machines in which both members of the printing couples may not be cylinders.

What is claimed is:

1. In an intaglio printing machine, the combination with a plurality of printing couples, of means for simultaneously stopping and starting the printing operation of the couples, means for independently stopping the printing operation of any couple, and means for silencing the simultaneously operating means when an independently operating means is actuated.

2. In an intaglio printing machine, the combination with a plurality of printing couples, of an actuator common to the couples, means for manipulating the actuator to simultaneously start or stop the printing operation of the couples, means independent 125

of the actuator for stopping or starting the printing operation of any couple, and connections whereby the actuator is rendered inoperative when an independent means is manipulated.

3. In an intaglio printing machine, the combination with a pair of spaced printing couples, of an actuator located between the couples and common to both, connections whereby the actuator may be manipulated for simultaneously stopping or starting the printing operation of the couples, means located adjacent each couple for independently stopping or starting the printing operation thereof, and connections whereby the actuator is rendered inoperative when any of the independent couple-stopping means are manipulated.

4. In an intaglio printing machine, the combination with a plurality of printing couples spaced apart, each including a form and impression cylinder for perfecting a web, of a clutch actuator located between the couples and common to both for simultaneously stopping or starting the printing operation of the couples, means for independently stopping or starting the printing operation of any couple, manipulating mechanism for the actuator, and connections whereby the operation of an independent means operates the actuator mechanism to render the actuator inoperative.

5. In an intaglio printing machine, the combination with a plurality of printing couples, of a movable clutch actuator, connections whereby when the actuator is moved in one direction the couples are moved into printing relation and when the actuator is moved in the other direction the couples are moved out of printing relation, and means independent of the actuator for moving the members of any couple into or out of printing relation with each other.

6. In an intaglio printing machine, the combination with a pair of movable impression cylinders and coöperating form cylinders, of a movable clutch actuator common to both the impression cylinders, and connections whereby when the clutch actuator is moved in one direction the impression cylinders are thrown into printing relation with the coöperating form cylinders and when the actuator is moved in the other direction the impression cylinders are moved out of printing relation with the coöperating form cylinders.

7. In an intaglio printing machine, the combination of a plurality of printing couples each including form and impression cylinders, the form cylinders being constantly running and the impression cylinders being vertically adjustable to and from the form cylinders, of an actuator, a shaft therefor, connections from the shaft for lifting the impression cylinder of one of the

couples, a second shaft, connections therefrom for lifting the impression cylinder of the other couple, and connections whereby the actuator may operate both shafts for simultaneously lifting both impression cylinders. 70

8. In an intaglio printing machine, the combination of a pair of impression cylinders, a pair of shafts, connections from the shafts for lifting the impression cylinders, 75 an actuator slideable on one of the shafts having oppositely disposed clutch faces, co-operating clutch members on each of the shafts at opposite sides of the actuator, and connections whereby when the actuator is in 80 clutched relation with the clutch members the shafts are rotated together and the impression cylinders simultaneously raised or lowered.

9. In an intaglio printing machine, the combination with a pair of impression cylinders, of a shaft, connections from the shaft to one of the impression cylinders for moving the latter, a second shaft, connections from the second shaft to the other impression cylinder for moving the latter, an actuator block slideable and rotatable on one of the shafts, clutch teeth on oppositely disposed faces of the block, clutch members fast on the block shaft, a clutch member 90 loose on the block shaft, a clutch member fast on the second shaft, said clutch members having teeth arranged to be engaged by the teeth on the block, and means for operating the block in either direction to bring it into 95 engagement with the clutch members.

10. In an intaglio printing machine, the combination with a pair of impression cylinders, of a shaft, connections from the shaft to one of the impression cylinders for moving the latter, a second shaft, connections from the second shaft to the other impression cylinder for moving the latter, an actuator block slideable and rotatable on one of the shafts, clutch members fast on the block 105 shaft, a clutch member loose on the block shaft, a clutch member fast on the second shaft, said clutch members having teeth arranged to be engaged by the teeth on the block, a worm gear on the block, and an operating shaft having a coöperating worm wheel. 110

11. In an intaglio printing machine, the combination with a pair of impression cylinders, of a shaft, connections from the shaft to one of the impression cylinders for moving the latter, a second shaft, connections from the second shaft to the other impression cylinder for moving the latter, an actuator block slideable and rotatable on one of the shafts, clutch teeth on oppositely disposed faces of the block, clutch members fast on the block shaft, a clutch member loose on the block shaft, a clutch member fast on the other shaft, a cross shaft, gears 120 125 130

thereon coöperating with gear teeth on the clutch members, and means for sliding the actuator in either direction for causing it to rotate the cylinder operating shafts simultaneously.

12. In an intaglio printing machine, the combination with a pair of impression cylinders, of a shaft, connections from the shaft to one of the impression cylinders for moving the latter, a second shaft, connections from the second shaft to the other impression cylinder for moving the latter, an actuator block slideable and rotatable on one of the shafts, clutch teeth on oppositely disposed faces of the block, clutch members fast on the block shaft, a clutch member loose on the block shaft, a clutch member fast on the second shaft, the clutch members fast on the block shaft being positioned in recesses in the other clutch members, the clutch members being provided with coinciding clutch teeth, and means for operating the actuator block in either direction to bring the clutch teeth thereon into engagement with the teeth of the clutch members.

13. In an intaglio printing machine, the combination of a pair of impression cylinders, a pair of shafts, connections from the shafts for moving the impression cylinders,

an actuator freely slideable longitudinally of and rotatable on one of the shafts, said actuator having oppositely disposed clutch faces, coöperating clutch members on each of the shafts at opposite sides of the actuator, and connections whereby when the actuator is in clutched relation with the clutch members the shafts may be rotated simultaneously in either direction and the impression cylinders simultaneously raised or lowered.

14. In an intaglio printing machine, the combination of a pair of impression cylinders, a pair of shafts, connections from the shafts for moving the impression cylinders, an actuator freely slideable longitudinally of and rotatable on one of the shafts, said actuator having oppositely disposed clutch faces, coöperating clutch members on each of the shafts at opposite sides of the actuator, connections whereby when the actuator is in clutched relation with the clutch members the shafts may be rotated simultaneously in either direction and the impression cylinders simultaneously raised or lowered, and means for moving the impression cylinders independently of each other.

In testimony whereof, I have hereunto set my hand.

ISIDOR TORNBERG.
